UNITED STATES PATENT OFFICE.

JACOB E. NEAHR, OF HARTSDALE, NEW YORK.

MATCH SAFE.

Application filed October 4, 1923. Serial No. 666,449.

This invention relates to match-safes and their appurtenances, including match-strikers, ash-receivers, cigar-extinguishers, etc.

One of the main objects of the invention is to make it practicable to reduce the cost of producing and marketing articles of this character, and to simplify and improve their construction and appearance. In this construction the match-safe is inserted within a bowl or receptacle which serves as an ash-receiver, a cover being provided for the bowl. The cover preferably has provision for striking matches thereon.

One of the main features of the invention resides in so organizing the match-safe, and the cover, with their appurtenances, that the whole forms a single unit, which unit can be manufactured and sold as a separate article of commerce, and is readily applied to such bowl as may be secured by the retailer from other sources. The bowls may be made of glass, ceramic ware, wood or other material, and need not be manufactured by the producer of said unit. Hence the manufacturer of the match-safe does not need to provide an expensive equipment for manufacturing bowls, nor does he need to invest capital in procuring bowls to sell in connection with the match-safes and covers. It is only necessary for him to manufacture the match-safe and cover, and furnish such unit to the retailer, who can select his bowls from a variety of sources, and merely place the cover and match-safe unit thereon, thus producing a simple, attractive and salable article for smokers' use.

Other features and advantages will hereinafter appear.

In the accompanying drawings, Figure 1 is a plan in one form of the unit comprising the new article of manufacture; the bowl to which it is applied being shown in dotted lines in the various figures.

Figure 2 shows the cover swung back and its under side exposed; the end of a cigarette being indicated in dotted lines, as being extinguished.

Figure 3 is a sectional side elevation of the new article of manufacture.

Figure 4 is an edge view of the same.

Figure 5 is a separate view of the partition device.

The cover 10 is designed for a circular ash-receiving bowl 11, although other than round forms for the ash-receptacle and cover may be adopted within the scope of the in-

vention. This cover is in the nature of a flat segmental plate, having one straight edge 12, where the cover is hinged at 13 to a match-safe 14, which is inserted in the ash-receptacle or bowl, said safe having a straight side 15, and the cover being hinged thereto at the top edge of said straight side. The remainder of the match-safe may be curved at 16 to form a segment and conform to and be supported partly by the interior of the ash-receptacle, which, in the illustrated form, is round. Upon its upper edge, opposite from the hinge, the match-safe is provided with a hook 17, which catches upon the edge of the bowl and partly supports the match-safe; the latter being partly supported upon the cover by means of the hinge.

The hook may be attached to the match-safe in the following manner: A partition device 18 resembling a box is inserted in the match-safe, and the hook 17 is formed upon one side 19 of the partition device, Figure 5, the latter consisting of also two partitions 20, 21, serving to divide the match-safe into three compartments. The disclosed unit will accommodate itself to a variety of sizes of bowls, the brims whereof may have a variety of forms and thicknesses; and the hook 17 may be re-shaped or bent to accommodate the brim of any bowl. After this is done, the partition device may be replaced in the match-safe, and may then be secured by means of a tongue 22 cut from the match-safe and pressed inwardly into an opening 23 provided in the side 19 of the partition device.

In the cover 10 is provided a slot or opening 24 through which burnt matches and other refuse may be dropped into the ash-receptacle. Between said opening and the main curved edge of the cover is a match-striking aperture 25, and beneath this aperture is a receptacle or pocket 26 in the form of a slideway, into which may be slidden endwise the sides 27 broken off from an ordinary paper box of safety-matches; these sides having the usual match-striking preparation forming a coating thereon.

At the ends of the opening 24 there may be provided upon the cover cigar-rests 28, elevated above the cover; these cigar-rests preferably struck up from the metal plate of which the cover is formed.

On its under side the cover may be provided, near its hinge side, with a cigar-ex-

tinguisher in the form of converging plates or lips 29, 30, between which the lighted end of a cigar 30^a may be thrust to pinch and extinguish the cigar. There is also preferably provided, in the crotch of the converging plates 29, 30, a spring blade 31 or the like, which is preferably bowed, and is pressed back by the cigar end, and which, when recovering itself as the cigar is withdrawn, cleans or tends to clean away the cigar-ashes from the surfaces of the converging plates. This spring cleaning-blade may be suitably supported at its ends upon a bracket-plate 32 fixed to the under side of the cover; the support for the spring blade being of such a nature as to allow an end-wise play of the blade while it is being pressed back. At its ends the blade may be hooked at 33 over ears 34 formed on the bracket-plate 32, Figure 4.

Variations may be resorted to within the scope of the invention, and portions of the improvements may be used without others.

Having thus described my invention, I claim:

1. A new article of manufacture in the form of a match-safe, and a cover hinged to the top thereof to form an article for placing in an ash-receiver or bowl.
2. A new article of manufacture in the form of a match-safe, and a cover hinged to the top thereof to form an article for placing in an ash-receiver or bowl, the same formed to set within the bowl, and the cover formed to extend over the edge of the bowl to partly support the safe.
3. A new article of manufacture in the form of a match-safe, and a cover hinged to the top thereof to form an article for placing in an ash-receiver or bowl, the safe formed to set within the bowl, the cover formed to extend over the edge of the bowl to partly support the safe, and said cover having an opening through which to drop burnt matches and refuse into the bowl, and also having an aperture through which an ignition-strip may be exposed, and having beneath said aperture a pocket open at one end and fitted to receive the sides of safety-match boxes to be exposed through said aperture.
4. A new article of manufacture in the form of a match-safe, and a cover hinged to the top thereof to form an article for placing in an ash-receiver or bowl, said safe having means to hook over the edge of the bowl, to partly support the safe thereon, said match-safe provided with an interior partition device and said hooking means being connected to said partition device.

5. A new article of manufacture in the form of a match-safe, a cover hinged to the top thereof to form an article for placing in an ash-receiver or bowl, said safe having means to hook over the edge of the bowl, to

partly support the safe thereon, said match-safe provided with an interior partition device and said hooking means being connected to said partition device, said partition device having a box-like form, sides of the box forming the partitions, and another side of the box having said hooking means, and interlocking means in the box and match-safe to hold the box in place.

6. A new article of manufacture in the form of a match-safe, and a cover hinged to the top thereof to form an article for placing in an ash-receiver or bowl, the safe formed to set within the bowl, and the cover formed to extend over the edge of the bowl to partly support the safe, said match-safe having one side to extend straight across the bowl and its remaining sides being of a contour to match the interior of the bowl to match the interior of the bowl.

7. A new article of manufacture in the form of a match-safe, and a cover hinged to the top thereof to form an article for placing in an ash-receiver or bowl, said safe having means to hook over the edge of the bowl, to partly support the safe thereon, said match-safe having one side to extend straight across the bowl and its remaining sides being of a contour to match the interior of the bowl, and said cover hinged to said match-safe at the top of its straight side.

8. A new article of manufacture in the form of a match-safe, and a cover hinged to the top thereof to form an article for placing in an ash-receiver or bowl, the safe formed to set within the bowl, and the cover formed to extend over the edge of the bowl, to partly support the safe, said safe having means to hook over the edge of the bowl, to partly support the safe thereon, said match-safe having one side to extend straight across the bowl and its remaining sides being of a contour to match the interior of the bowl, said cover hinged to said match-safe at the top of its straight side, and said cover having an opening through which to drop burnt matches and refuse into the bowl, and also having an aperture through which an ignition-strip may be exposed, and having beneath said aperture a pocket open at one end and fitted to receive the sides of safety-match boxes to be exposed through said aperture.

9. A new article of manufacture in the form of a match-safe, and a cover hinged to the top thereof to form an article for placing in an ash-receiver or bowl, said cover having on its under side a cigar-extinguisher.

10. A new article of manufacture in the form of a match-safe, and a cover hinged to the top thereof to form an article for placing in an ash-receiver or bowl, said cover having on its under side a cigar-extinguisher in the form of converging jaws or lips into which the lighted end of the cigar is thrust.

11. A new article of manufacture in the form of a match-safe, and a cover hinged to the top thereof to form an article for placing in an ash-receiver or bowl, said cover having on its under side a cigar-extinguisher in the form of converging jaws or lips into which the lighted end of the cigar is thrust, a yielding device being provided at the convergence of said jaws in position to be pressed back by the end of the cigar, and to clear away ashes when recovering its normal form.
12. A new article of manufacture in the form of a match-safe, a cover hinged to the top thereof to form an article for placing in an ash-receiver or bowl, said cover having on its under side a cigar-extinguisher in the form of converging jaws or lips into which the lighted end of the cigar is thrust, a yielding device being provided at the convergence of said jaws in position to be pressed back by the end of the cigar, and to clear away ashes when recovering its normal form.
13. A new article of manufacture in the form of a match-safe, a cover hinged to the top thereof to form an article for placing in an ash-receiver or bowl, said cover having on its under side a cigar-extinguisher in the form of converging jaws or lips into which the lighted end of the cigar is thrust, a yielding device being provided at the convergence of said jaws in position to be pressed back by the end of the cigar, and to clear away ashes when recovering its normal form.

in an ash-receiver or bowl, said cover having on its under side a cigar-extinguisher in the form of converging jaws or lips into which the lighted end of the cigar is thrust, a yielding device being provided at the convergence of said jaws in position to be pressed back by the end of the cigar, and to clear away ashes when recovering its normal form, said yielding device in the form of a member extending between said lips from one side to the other and projecting from said lips, and means holding said yielding device at its ends.

JACOB E. NEAHR.
